UNITED STATES PATENT OFFICE.

WINSLOW W. DUNN, JR., OF ST. PAUL, MINNESOTA.

DESIGN FOR AN ELECTRIC-LIGHT SHADE.

Application filed January 22, 1923. Serial No. 4,959. Term of patent 14 years.

To all whom it may concern:

Be it known that I, WINSLOW W. DUNN, Jr., a citizen of the United States, residing at St. Paul, in the county of Ramsey and State of Minnesota, have invented a new, original, and ornamental Design for Electric-Light Shades, of which the following is a specification, reference being had to the accompanying drawing, forming part thereof.

Figure 1 is a side elevation of the new and ornamental design for shades.

Figure 2 is a plan view of the same.

I claim:

The ornamental design for an electric light shade, as shown.

St. Paul, Minnesota, January 16, 1923.
